UNITED STATES PATENT OFFICE.

HOWARD A. WOLF, OF ELKINS PARK, PENNSYLVANIA, ASSIGNOR, BY MESNE ASSIGNMENTS, TO HOWARD WOLF, BENJAMIN WOLF, ELIAS WOLF, LOUIS WOLF, AND ALBERT WOLF, ALL OF PHILADELPHIA, PENNSYLVANIA, COPARTNERS, DOING BUSINESS AS WOLF BROTHERS, OF PHILADELPHIA, PENNSYLVANIA.

PAPER BAG.

Application filed November 9, 1928. Serial No. 147,207.

My invention relates to improvements in paper bags, and more particularly to that type of bag which is provided with finger holes and conveniently used for carrying small articles of merchandise.

Bags of the character to which my invention relates have been produced in various forms and have found a wide use in department stores and the like, since they afford a convenient means for packaging small articles and are conveniently carried by the customer. Such bags, while they are to a substantial extent satisfactory, are open to a number of objections chief among which are that they tend to open in use and that when carried they do not afford a comfortable grip, or bearing, for the fingers.

Now it is the object of my present invention to provide a bag, of the type indicated, so constructed as to with certainty remain closed and to afford a substantial bearing for the finger when carried.

Having now indicated, in a general way, the nature and purpose of my invention, I will proceed to a detailed description thereof with reference to the accompanying drawings in which there is illustrated a preferred embodiment and in which:

Figure 1 is a rear view of an end portion of a bag, embodying my invention, in open position.

Figure 1^A is a partial rear view of a closing flap showing a modified locking tongue.

Figure 2 is a diagrammatic view of a portion of the bag shown in Figure 1.

Figure 3 is a rear view of the subject of Figure 1 showing the bag closed.

Figure 4 is a diagrammatic view of a portion of the bag shown in Figure 2.

Figure 5 is a rear view of the subject of Figure 1, showing the closing flap locked in closed position and the bag ready to be carried.

Figure 6 is a diagrammatic view of a portion of the bag shown in Figure 5.

Figures 7, 8 and 9 are views similar to those of Figures 1, 3 and 5 showing a modification.

Referring to the drawings and more particularly to Figures 1-6 inclusive, the bag, which is preferably formed by bending a single sheet, or blank, upon itself and secur-

ing the side edges, the top being left open, comprises a front wall *a* and a rear wall *b*. The front wall is extended to form a closing flap *c*, which acts to close the open end of the top and a locking tongue *d*, the ends of which extend at an angle to one another is formed integral with the closing flap, as by an extension thereof, as shown in Figure 1, or, if desired, within the flap as shown in Figure 1^A.

The front and back walls of the bag are provided with apertures *e* of a width slightly greater than that of the tongue *d* and the ends of which extend at an angle to each other oppositely to that of the extension of the ends of the tongue *d*.

To the front wall is secured a reinforcement piece *f* apertured in line with aperture *e* and extending to the edge of the flap *c* and over tongue *d*. A reinforcement piece *g* apertured in alignment with the aperture *e*, in the back wall, is secured to the back wall.

A crease, indicated by dotted line *h*-*h* is formed from side to side of the bag, in the front wall and reinforcement *f*, on approximately the line of juncture of the front wall and its extension forming flap *c*, and a crease, indicated by dotted line *i*-*i* is formed on the line of juncture of the flap *c* and the extension thereof forming tongue *d*.

A third crease, indicated by dotted line *j*-*j* is formed in the reinforcement *f* on a line about midway between the creases indicated by dotted lines *h*-*h* and *i*-*i*.

The bag as shown in Figures 1 and 2 is ready for use. After the deposit within the bag of articles to be carried, the closing flap *c* is folded down on crease line *h*-*h* and assumes the position shown in Figures 3 and 4. The locking tongue *d* is then passed through the aligning apertures *e*, through which it easily passes, in the front and back walls and bent up behind the front wall on crease line *i*-*i*.

The fingers are then passed through the aligning apertures *e*, preferably from the back to the front. When the weight of the bag is taken on the fingers the flap will bend on the crease line *j*-*j* and assume the position shown in Figures 5 and 6, causing the tongue *d* to be held in a position where its greatest width coincides with the least width

of the apertures, thus causing the upper portions of its end portions to engage the front wall of the bag and prevent it from passing back through openings *e*, or in other words cause the tongue to be locked. The bending of the reinforcement on crease line *j-j* will also have the effect of providing a full three dimensional handle or bearing for the fingers enabling the bag to be carried with convenience and without discomfort.

Referring now to Figures 7, 8 and 9, the bag illustrated is similar to that illustrated in Figures 1-6, the similar parts being denoted by similar reference symbols, except that ends of the aligning apertures *e'* are stepped as indicated at *k* and the ends of the locking tongue *d'* stepped as indicated at *l*. The tongue *d'* and apertures *e'* are oppositely stepped so that the tongue will initially pass easily through the apertures, as indicated in Figure 8, but will lock, by engagement of the upper portions of its ends with the front wall, after it is bent up into locking position as shown in Figure 9. The locking tongue *d'* may, it will be appreciated, be formed within the flap rather than as an extension thereof, if desired, as indicated in connection with tongue *d*.

The bag illustrated in Figures 7, 8 and 9 is used in the same manner as is the bag illustrated in Figures 1-6 inclusive.

Having now fully described my invention, what I claim and desire to protect by Letters Patent is:

1. A paper bag including connected back and front walls separated at their upper ends to form an opening for the bag, a closing flap formed as an extension of the upper end of one of the walls, said flap being creased on a line adjacent the opening whereon it may be folded to close the opening, and a locking tongue hinged to the closing flap, said front and back walls being formed with aligning apertures spaced from the crease in the flap a distance less than that between the crease and the hinge line of the tongue, whereby, when the flap is folded over the opening along the crease and the tongue passed through the aligned apertures with its hinge line at the upper edge of an aperture, the flap will extend outwardly from the walls of the bag forming a handle.

2. A paper bag including connected back and front walls separated at their upper ends to form an opening for the bag, a closing flap formed as an extension of the upper end of one of the walls, and a locking tongue hinged to the closing flap, said front and back walls being formed with aligning apertures spaced from the upper ends of the walls a distance less than that between the upper ends of the walls and the hinge line of the tongue, whereby, when the flap is folded over the opening and the tongue passed through the aligned apertures with its hinge line at the upper

edge of an aperture, the flap will extend outwardly from the walls of the bag forming a handle.

3. A paper bag including connected back and front walls separated at their upper ends to form an opening for the bag, a closing flap formed as an extension of the upper end of one of the walls, said flap being creased on a line adjacent the opening whereon it may be folded to close the opening, and a locking tongue hinged to the closing flap, said front and back walls being formed with aligning apertures spaced from the crease in the flap a distance less than that between the crease and the hinge line of the tongue, and said closing flap being creased between the first crease and the hinge line of the tongue, whereby, when the flap is folded over the opening along the crease and the tongue passed through the aligned apertures with its hinge line at the upper edge of an aperture, the flap will extend outwardly from the walls of the bag forming a handle.

4. A paper bag including connected back and front walls separated at their upper ends to form an opening for the bag, a closing flap formed as an extension of the upper end of one of the walls, and a locking tongue hinged to the closing flap, said front and back walls being formed with aligning apertures spaced from the upper ends of the walls a distance less than that between the upper ends of the walls and the hinge line of the tongue, and said closing flap being creased between the upper ends of the walls and the hinge line of the tongue, whereby, when the flap is folded over the opening and the tongue passed through the aligned apertures with its hinge line at the upper edge of an aperture, the flap will extend outwardly from the walls of the bag forming a handle.

5. A paper bag including connected back and front walls separated at their upper ends to form an opening for the bag, a closing flap formed as an extension of the upper end of one of the walls, said flap being creased on a line adjacent the opening whereon it may be folded to close the opening, a reinforcement piece secured to the closing flap, and a locking tongue hinged to the closing flap, said front and back walls being formed with aligning apertures spaced from the crease in the flap a distance less than that between the crease and the hinge line of the tongue, and said reinforcement piece being creased between the first crease and the hinge line of the tongue, whereby, when the flap is folded over the opening along the crease and the tongue passed through the aligned apertures with its hinge line at the upper edge of an aperture, the flap will extend outwardly from the walls of the bag forming a handle.

6. A paper bag including connected back and front walls separated at their upper ends to form an opening for the bag, a closing flap

formed as an extension of the upper end of one of the walls, a reinforcement piece secured to the closing flap, and a locking tongue hinged to the closing flap, said front and back walls being formed with aligning apertures spaced from the upper ends of the walls a distance less than that between the upper ends of the walls and the hinge line of the tongue, and said reinforcement piece being creased 10 between the upper ends of the walls and the hinge line of the tongue, whereby, when the flap is folded over the opening and the tongue passed through the aligned apertures with its hinge line at the upper edge of an aperture, the flap will extend outwardly from the walls 15 of the bag forming a handle.

In testimony of which invention, I have hereunto set my hand, at Philadelphia, Penna., on this 6th day of November, 1926.

HOWARD A. WOLF.
